D. C. KITCHING,
ADJUSTABLE VEHICLE HEADLIGHT,
APPLICATION FILED APR. 23, 1914.

1,111,724.

Patented Sept. 22, 1914.

UNITED STATES PATENT OFFICE.

DAVID C. KITCHING, OF VALLEY MILLS, TEXAS.

ADJUSTABLE VEHICLE-HEADLIGHT.

1,111,724.

Specification of Letters Patent. Patented Sept. 22, 1914.

Application filed April 23, 1914. Serial No. 833,827.

To all whom it may concern:

Be it known that I, DAVID C. KITCHING, a citizen of the United States, residing at Valley Mills, in the county of Bosque and State of Texas, have invented certain new and useful Improvements in Adjustable Vehicle-Headlights, of which the following is a specification.

My invention relates to new and useful improvements in adjustable vehicle headlights and relates particularly to certain improvements upon the device covered in my co-pending applications filed December 15, 1913, Serial No. 806,687 and February 7, 1914, Serial No. 817,213.

It is the object of my invention to provide a vehicle headlight which by means of a suitable manually actuated mechanism may be so swung so as to direct its rays to either side of the road or track along which the vehicle is moving, and which will be instantly and automatically returned to its normal position as soon as the adjusting mechanism is released.

The object of my invention more specifically stated, is to mount a vehicle headlight upon a support and impress upon said support by means of two coiled springs opposite rotative impulses which when the lamp is displaced angularly from its normal position will tend to immediately return it to said position.

A still further object of the invention is to provide a device of the character described, that will be strong, durable, efficient and simple and comparatively inexpensive to produce, also one in which the several parts will not be likely to get out of working order.

With the above and other objects in view, the invention has relation to certain novel features of construction and operation, an example of which is described in the following specification and illustrated in the accompanying drawings, wherein:

Figure 1 is a view showing in side elevation the front extremity of an electric car of the interurban type, showing my novel headlight adjusting mechanism correlated with the car. Fig. 2 is a vertical axial view of the standard upon which I mount an adjustable vehicle headlight. Fig. 3 is a transverse sectional view taken upon the line $x-x$ of Fig. 2. Fig. 4 is a transverse sectional view taken upon the line $y-y$ of Fig. 2.

Referring now more particularly to the drawing, wherein like reference characters designate similar parts in all the figures, the numeral 1 denotes the headlight of an interurban car, which is rigidly supported in a yoke formed by curved arms 2, having their upper extremities rigidly engaging in lugs 3 carried at each side of the headlight. At their lower ends, the arms 2 have integral connection with a circular horizontal plate 4 formed upon its underside with an integral interiorly threaded collar 5. Within the collar 5, there is engaged the threaded upper end of an elongated vertical cylinder 6, through which are passed electric wires 8, conducting current to the headlight, the plate 4 being centrally apertured to give passage to said wires. The cylinder 6 is spaced within a somewhat larger vertical cylinder 9, longitudinally split into equal halves, which are held in their proper opposed relation by a pair of nuts 10 one of which is screwed fast on either side of the cylinder 9. The upper extremity of the cylinder 9 loosely receives the collar 5, and the lower extremities of the two cylinders are held concentric by a set-collar 11, fast upon the cylinder 6.

The cylinder 9 is rigidly secured to the front end of a car by a pair of angular brackets having parallel portions 11^a into which the extremities of the cylinder are respectively threaded, their other portions 11^b being contiguous with the front wall of the car and bolted thereto. The portion 11^a of the uppermost bracket constitutes a thrust bearing for the collar 4, thus supporting the weight of the headlight and of the inner cylinder which depends from the collar 4.

Upon the cylinder 6, there are mounted two coiled springs respectively above and below the center of said cylinder, each spring comprising two equal parts 12 and 13, oppositely pitched. The integrally joined end portions of the parts 12 and 13 of each spring meet each other at an angle, within the apex of which a pin 14 projects slightly from the cylinder 6. The other end of the parts 12 and 13 of said springs are secured to vertically alined bolts 15, which are passed through the wall of the cylinder 9 at the back thereof. The parts 12 and 13 of the upper coiled spring are pitched oppositely to the corresponding parts of the lower spring, so that the two

springs resist each other in their tendencies to impart a rotation to the cylinder 6 and to the headlight. The counteracting forces exerted by the two springs tend to maintain the headlight in a position such that its rays are directed straight ahead of the car.

The lower end of the cylinder 9 projects slightly beneath the lowermost bracket member 11^a to engage with a pipe elbow 15^a, making a ninety degree turn toward the car and closed at its other end by a cap 16. Within the elbow 15^a there is mounted a pair of intermeshed bevel gears 17, one of which is rigidly carried by the lower end of the cylinder 6 and the other mounted fast upon the front end of a horizontal shaft 18 passing loosely through a bushing 18^a held by the cap 16. The shaft 18 is extended rearwardly into the vestibule of the car passing through the front wall of the same.

Within the car adjacent to its front wall, a vertical rock-shaft 20 is mounted, and is adapted to communicate rotation to the shaft 18 through a pair of bevel gears 21. At its upper extremity, the rock-shaft 20 is formed with an integral handle 22, whereby rotation may be manually imparted to said rock-shaft.

The various features of the construction having been covered in the foregoing discussion, an explanation will now be given as to the operation of my invention.

The motorman, when desiring to illuminate a curve, will throw the handle 22 to the right or left, according to the direction of curvature of the track. The cylinder 9 being firmly engaged by the two brackets comprised by the parts 11^a and 11^b, will not participate in the rotation communicated to the headlight and to the cylinder 6 through the shafts 18 and 20. When the headlight is being adjusted to throw its rays to the right of the track, the uppermost spring will be distorted through the displacement communicated to the joined ends of the members 12 and 13 by the correlated pin 14. The rotation to which the cylinder 6 is subjected in accomplishing this adjustment of the headlight is not such as to produce distortion of the lower coiled spring, since the pin 14 correlated with said spring will be shifted into a spaced relation with the joined ends of the parts 12 and 13 of said spring. Similarly, it is apparent that during adjustment of the lamp to throw its rays to the left of the track, the lowermost spring will be subjected to distortion, while the upper spring will not be affected. Whether the adjustment of the headlight is such as to produce illumination at the right or left of the track, the spring which is distorted will in each case tend to return the headlight to a normal position in which its rays will be directed straight ahead of the car.

While my novel adjusting mechanism in

this instance is shown correlated with an electric car, it is to be understood that the mechanism is furthermore adapted for use in connection with locomotives, automobiles and various other vehicles.

The invention is presented as including all such modifications and changes as properly come within the scope of the following claims.

What I claim is:

1. In a device of the character described, the combination with two vertical cylinders, spaced one within the other, the outer one being rigidly supported, of a headlight surmounting the inner cylinder, a pair of springs coiled upon the inner cylinder, each having a connection with the outer cylinder, opposite rotative impulses being exerted by said springs upon the inner cylinder, and means for subjecting the inner cylinder to rotation.

2. In a device of the character described, the combination with two vertical cylinders, spaced one within the other, the outer one being rigidly supported, of a headlight surmounting the inner cylinder, a pair of springs coiled upon the inner cylinder having their ends made fast to the outer cylinder, a loop being formed at the center of each spring from which it passes around 95 said cylinder in the same direction in extending toward the ends, a pin projecting rigidly from the inner cylinder into each loop, one of said pins producing distortion of the springs for rotation of the inner cylinder in a certain direction, and the other pin producing distortion of its correlated spring for rotation of the cylinder in the other direction, and means for subjecting the inner cylinder to rotation.

3. In a device of the character described, the combination with a vertical cylinder, of a headlight superimposed thereupon, a pair of springs coiled upon said cylinder, having their extremities made fast in a vertical 110 alignment adjacent to the cylinder, a loop being formed at the center of each spring, from which its coils are passed around the cylinder, a pin projecting rigidly from the cylinder into each loop, one of said pins subjecting the correlated spring to distortion during rotation of the cylinder in a certain direction, and subjecting the correlated spring to distortion in the other direction, and means for subjecting the cylinder to 115 rotation.

4. In a device of the character described, the combination with two vertical cylinders spaced one within the other, the outer one being rigidly supported, of a cap mounted 125 upon the lower end of the outer cylinder, supporting the weight of the inner cylinder, means maintaining the proper spaced relation of the two cylinders at their upper ends, a headlight surmounting the inner cylinder,

a pair of springs coiled upon the inner cylinder, each having a connection with the outer cylinder, opposite rotative impulses being exerted by said springs upon the inner cylinder, and means for communicating rotation to the inner cylinder.

5 In testimony whereof I have signed my

name to this specification in the presence of two subscribing witnesses.

DAVID C. KITCHING.
